DUAL CAR SEAT FOR CHILDREN

George B. Walker and Wayne E. Walker, both of Rte. 2,
Box 557, Itta Bena, Miss. 38941

Filed July 11, 1966, Ser. No. 3,015

Term of patent 14 years

(Cl. D15—1)

FIG. 1

FIG. 2

FIG. 5

FIG. 4

FIG. 3

FIG. 1 is a perspective view of a dual car seat for children embodying our new design.

FIG. 2 is a top plan view of a dual car seat for children embodying our new design.

FIG. 3 is a rear elevational view with parts broken away for convenience.

FIG. 4 is a front elevational view with parts similarly broken away.

FIG. 5 is a side elevational view from one side of the device, the opposite side of the device being substantially identical in reverse.

We claim:

The ornamental design for a dual car seat for children, substantially as shown and described.
